(57) **CLAIM**

The ornamental design for the tiered cake shaped structure to conceal a person, as shown and described.

DESCRIPTION

FIG. 1 is a perspective front view of a tiered cake shaped structure to conceal a person, showing my new design, in an assembled condition;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a plan view of an unassembled top blank that forms a portion of the top tier of the cake shaped structure as shown in FIGS. 1-7;

FIG. 9 is a plan view of an unassembled middle blank that forms a portion of the middle tier of the cake shaped structure as shown in FIGS. 1-7; and,

FIG. 10 is a plan view of an unassembled bottom blank that forms a portion of the bottom tier of the cake shaped structure as shown in FIGS. 1-7.

The lightweight broken line portion of the FIG. 8 shows unclaimed usage environment subject matter only and forms no part of the claimed design. The dot-dash style broken lines in FIGS. 8, 9, and 10 show claim boundaries only and form no part of the claimed design.
